UNITED STATES PATENT OFFICE.

JENS WESTLY, OF CHRISTIANSAND, NORWAY, ASSIGNOR TO DET NORSKE AKTIESEL-SKAB FOR ELEKTROKEMISK INDUSTRI OF NORWAY, OF OSLO, NORWAY.

SELF-BAKING ELECTRODE.

Application filed January 5, 1925, Serial No. 711, and in Norway January 17, 1924.

This invention relates to selfbaking electrodes, that is, electrodes which are baked in the furnace in which they are used, and the object of the invention is the provision 5 of a contact supplying electric current to the electrode without substantial loss of voltage.

In U. S. Patent No. 1,440,724 there is described "self-baking" electrodes provided 10 with metallic mantles. In said patent it is stated that one of the functions of the mantle is to transmit the current to the electrode, which function is facilitated by the employment of ribs or similar attachments 15 projecting into the electrode mass and giving a good contact therewith. The electric current is generally supplied to the mantle and the electrode is also supported by means of an external electrode-holder 20 clamped tightly around the electrode. The contact thus obtained between holder and mantle is generally satisfactory. Some dust, however, may gather on the electrode mantle and during the displacement of the holder 25 more or less of this dust may be carried in between the contact surfaces, causing a certain resistance and consequent voltage loss. This loss of voltage is generally quite negligible compared with the total voltage 30 of the furnace. In certain special cases it may, however, be of importance to avoid this loss of voltage. An excellent example is the application of the electrode in furnaces for the production of aluminium, as the 35 total voltage of the furnace in this case is only 6,5-7 volts. If for instance the drop in voltage from holder to electrode is 0,35 volts this amounts to 5% of the total voltage. In furnaces for the production of 40 aluminium it has been proposed to supply electrodes with aluminium mantles. This metal readily becomes coated with a thin oxide film offering considerable resistance to the passage of the current. The loss of 45 voltage may therefore easily become relatively large and precautions should be taken to reduce the resistance. For this purpose I have found it desirable to employ a contact arrangement which in its principle is 50 shown in the drawing forming part of this application.

In the drawing Fig. 1 illustrates a modification in which the mantle is provided with a number of straps which 55 are bent so as to extend outwardly

from the electrode and to which the contact arrangements are firmly attached. Fig. 2 shows a contact arrangement clamped on to two straps. Figs. 3 and 4 are sections through Fig. 1. 1 is the electrode, 2 the 60 mantle and 3 one of the two straps which are held tightly between the two metal blocks 4 and 5 by means of the bolt and nut 6. Thus the contact becomes practically 65 perfect and little or no loss of voltage can be found in the contact. At the same time the arrangement possesses the advantage that the contacts may be raised one at a time while the other contacts maintain the 70 supply of current, no disturbance in the working being caused during the raising.

The independent electrical contacts may be made in different ways, for example by clamping to straps as above described, or by direct pressure against the surface of the 75 sheet metal, or by clamping conductors firmly against the surfaces of the externally projecting portions of the ribs, as herein-after described. If the current is supplied directly to the ribs the metallic mantle may 80 be left out and for instance be replaced by a mantle consisting of netting. If the netting is of sufficiently fine meshes it will 85 keep the mass inside during the baking.

The suspension of the electrode may be 85 effected by means of the contact arrangements, but it is preferable to employ a special supporting electrode-holder such as illustrated at 2^a Figure 1, which for instance 90 clamps around the electrode. In many cases it is advantageous to place the contact arrangement at a considerable height above 95 the bath. To reduce the drop in voltage it is often advantageous to reinforce the ribs or prolongations to which the contact arrangement is attached. This may for instance be done by casting aluminium around the external parts of ribs as shown in Fig. 3, in which 1 is the electrode, 2 the mantle and 3^a the metal cast around the external 100 parts of the ribs.

My contact arrangement may also be employed in connection with hollow selfbaking electrodes where the electric current is supplied through a contact arrangement placed in the channel. Such an arrangement is shown in U. S. Patent No. 1,442,031. The channel is provided with a suitable metal lining, for instance in the form of a tube having thin walls. The tube may if 110

desired be provided with holes to let out the gases formed during the baking of the electrode. The contact arrangement may for example be so made that it projects into the channel and grips around projections of the armature and (or) the extensions of the ribs. Fig. 4 shows an electrode provided with such extensions, in which figure, 1 is the electrode, 2^b the ribs having projections 3^b extending into the channel, and 4^b is the metal tube or lining.

It is of course to be understood that my invention is not limited to the above illustrations as its mode of application may vary according to the type of electrode used in each special case.

What I claim as new and desire to secure Letters Patent of the United States is:

1. In self-baking electrodes provided with metallic mantles, and electrode supporting means for controlling the position and feeding of the electrode, separate electrical contacting means independent of said electrode supporting means and adapted to introduce current into the electrode with a minimum loss in voltage at their contact therewith.

2. In self-baking electrodes provided with metallic mantles, electrical contacting means, attached to portions of said mantles and distinct from the electrode supporting means, adapted to minimize the voltage loss, where current is introduced into the electrode.

3. In electrodes of the kind described, a plurality of electrical contacting means, independent of the electrode supporting means and independently adjustable, adapted to introduce current into the electrode with a minimum drop in voltage at the contacts. 40

4. In electrodes of the kind described, independent electrical contacting means comprising conductors firmly attached to projecting portions of the metal mantle around the electrode, for the purpose of leading the 45 current into it.

5. Contact arrangement for self-baking electrodes provided with metallic mantles comprising a plurality of projections and conducting members attached thereto of 50 which a number smaller than the total number is capable of transmitting the current to the electrode.

6. In electrodes of the kind described, metallic ribs projecting radially from the 55 metallic mantle and adapted to make contact with electrical contact means in the external circuit and conduct the current into the electrode.

7. In electrodes of the kind described, outwardly extending metallic contact ribs forming integral continuations of the internal reinforcing ribs, and firmly attached to the mantle, and adapted to receive the electric current from the external circuit and transfer it to the electrode. 60 65

JENS WESTLY.
